UNITED STATES PATENT OFFICE

96,990

DESIGN FOR A JUG

Andrew S. Knapp, St. Louis, Mo., assignor to Knapp-Monarch Company, St. Louis, Mo., a corporation of Missouri

Application May 21, 1935, Serial No. 56,952

Term of patent 14 years

To all whom it may concern:

Be it known that I, Andrew S. Knapp, a citizen of the United States and a resident of the city of St. Louis and State of Missouri, have invented a certain new, original, and ornamental Design for a Jug, of which the following is a specification, reference being had to the accompanying drawing, forming part thereof.

I claim:

The ornamental design for a jug substantially as shown.

Des Moines, Iowa, May 4, 1935.

ANDREW S. KNAPP.
